UNITED STATES PATENT OFFICE

WILLIAM A. COOK, OF SHINNSTON, WEST VIRGINIA.

INSULATOR-CLAMP.

1,090,686.

Specification of Letters Patent. Patented Mar. 17, 1914.

Application filed April 9, 1913. Serial No. 760,061.

To all whom it may concern:

Be it known that I, WILLIAM A. COOK, a citizen of the United States, residing at Shinnston, in the county of Harrison and State of West Virginia, have invented certain new and useful Improvements in Insulator-Clamps; and I do hereby declare the following to be a full, clear, and exact description of the invention, such as will enable others skilled in the art to which it appertains to make and use the same.

This invention comprehends improvements in insulator clamps and relates more particularly to those which are especially adapted for holding telephone, telegraph, and electric wires of other descriptions upon an insulator.

The primary object of the invention is to provide a clamp of this nature, which shall be of extremely simple construction, cheap to manufacture, and which may be easily operated so as to permit the removal or attachment of a wire.

Another and more specific object of the invention is to provide an insulator clamp including a rigid member extending through an insulator, a movable member hinged to said rigid member and extending across the top of the insulator to engage a wire, and means for locking said movable member to the rigid member.

The invention also aims to generally improve devices of this nature to render them more useful, practical, and commercially desirable.

With these and other objects in view, as will become more apparent as the description proceeds, the invention consists in certain novel features of construction, combination, and arrangement of parts, as will be hereinafter described and claimed.

For a complete understanding of my invention, reference is to be had to the following description and accompanying drawings, in which,

Figure 1 is a side elevation of an insulator and support thereof, showing my improved clamp operatively attached to the former, Fig. 2 is an edge elevation looking against the left-hand side of Fig. 1, Fig. 3 is a vertical sectional view through my improved clamp and a portion of the insulator, taken on the plane of line 3-3 of Fig. 2, Fig. 4 is a fragmentary view of a portion of the removable clamp member, showing the construction of the latch, and, Fig. 5

is a section through the movable clamp member, taken on the plane of line 5-5 of Fig. 1.

Referring in detail to the drawing by numerals, 6 designates a preferably glass insulator, which is secured to a cross arm 7 by means of a clamping member 8.

In the preferred embodiment of my invention, the insulator 6 is formed adjacent its upper end with a transversely extending opening to receive a fixed clamp member, generally designated 9. This member comprises a bar 10, having a head 11 formed upon one end thereof and serrated to form teeth, as indicated at 12. A pivot bar 13 having a reduced and threaded end portion 14, which threads within an opening formed in one end of the bar 10, completes the rigid member of the clamp. Since this member is formed in sections as described and as clearly shown in Fig. 3, it may be easily positioned within the opening extending through the insulator.

A movable clamp member is pivotally secured to the angular extension 15 of the bar 13 and comprises a yoke 16 and lever 17. The yoke is formed at one end to embrace the angular extension 15 and is secured thereto by means of a pivot pin 18. The yoke extends over the top of the insulator and is formed with a centrally positioned jaw 19 which projects within a recess formed in the top of said insulator. The extremity of the jaw is made concave and formed with teeth 21, as clearly shown in Fig. 5, for the purpose of securely gripping a wire 22.

The lever 17 extends laterally from the free end of the yoke and is formed upon its under side with a longitudinal channel 23, for the purpose of receiving the locking means which I provide for securing the movable clamp member to the rigid clamp member. These locking means include a latch 24, which is slidable within the channel 23 and which is formed with a tooth 25 for engagement with the downwardly facing teeth 12. The latch is slidably secured in position by means of a strip 26, which is fixed at its ends to the walls of the channel 23 and which extends through a longitudinal slot 27 formed in said latch. A latch rod 28 is fixed to the outer end of the latch, extends through a guide 29, and is provided with a finger extension 30. An expansive spiral spring 31 surrounds that portion of the latch rod

which lies between the latch and the guide 29 and tends to hold the latch normally at the inner extremity of the channel 23.

From the foregoing description taken in connection with the accompanying drawing, it will be seen that I have provided an insulator clamp which may be easily unlocked to permit a wire being attached to or removed from an insulator and it is to be noted that 10 the serrated head 11 makes it possible to clamp wires of various diameters. The projection 25 being beveled upon its under side, as clearly shown in the drawings, renders the locking of the movable member automatic, for as can be readily seen, the beveled 15 face of the projection will cause the latch to move outwardly against the pressure of the spring 31.

It is to be understood that while I have 20 shown and described the preferred embodiment of my invention, I do not wish to be limited to this exact construction, combination, and arrangement of parts, but may make such changes as will fall within the 25 spirit and scope of the invention.

Having thus described my invention, what I claim is:—

1. The combination with an insulator, of an insulator clamp including a rigid member 30 having downwardly facing teeth formed on one end thereof, a movable member pivoted at one end to the other end of the fixed member and adapted to swing over the top of the insulator, a latch slideable upon the 35 movable member and means for forcing said latch toward the insulator, the latch being formed with a beveled face whereby it automatically engages under said teeth when the movable member is carried toward the insulator.

2. The combination with an insulator, of an insulator clamp comprising a fixed member 40 extending through said insulator having teeth formed upon one end thereof, a movable member pivoted to the other end of said fixed member and extending over the end of the insulator, and spring pressed locking

means carried by the movable member for automatic engagement with the teeth upon said fixed member when the movable member is swung toward the insulator.

3. The combination with an insulator, of an insulator clamp comprising a fixed member having teeth formed upon one end thereof, a movable member pivoted to the other end of said fixed member and extending over the end of the insulator, a latch slideably mounted upon said movable member, and means for automatically engaging said latch with the teeth when the removable member is forced toward the top of the insulator.

4. In combination with an insulator, an insulator clamp including a movable member pivoted to one side of said insulator, said movable member comprising a yoke extending over the end of the insulator and a lever formed upon the free end of the yoke, said lever being formed with a channel, a spring pressed latch slideable in said channel, and means carried upon the insulator for engagement by said latch whereby the movable member is held rigid.

5. The combination with an insulator, of an insulator clamp comprising a fixed member 75 extending transversely through said insulator and having teeth formed upon one end thereof, a movable member pivotally attached to the other end of said fixed member comprising a yoke extending over the end of the insulator, and a lever formed upon the 80 free end of the yoke, a latch slideable within a longitudinal channel formed in said lever, for engagement with the teeth, a latch rod having a finger extension thereon, and spring means surrounding said latch rod for 85 holding the latch normally at the extremity of its inward movement.

In testimony whereof I affix my signature in presence of two witnesses.

WILLIAM A. COOK.
